UNITED STATES PATENT OFFICE.

FRANK C. DORMENT, OF WELLINGTON, OHIO.

COMBINED AIR PURIFIER AND REFLECTOR.

Application filed September 21, 1923. Serial No. 663,969.

To all whom it may concern:

Be it known that I, FRANK C. DORMENT, a citizen of the United States, residing at Wellington, in the county of Lorain and

5 State of Ohio, have invented a certain new and useful Improvement in Combined Air Purifiers and Reflectors, of which the following is a full, clear, and exact description.

This invention relates to a combined air 10 purifier and reflector adapted to be applied to incandescent lamps, and has for its object to provide a vaporizing device for converting various substances into a gaseous state for medicinal and other purposes, adapted 15 to be mounted upon any standard size incandescent lamp bulb and to utilize the heat of said bulb to vaporize or volatilize the substance contained therein.

A further object is to provide a device 20 requiring no special electrical connections and adapted to be mounted upon the lamp fixtures already in place.

A further object of the invention is to provide a simple, efficient and inexpensive device 25 for disinfection and deodorization in a sick room, in public gathering places or in the home.

The present invention also furnishes a reliable means for the treatment and prevention 30 of infections, respiratory diseases by the inhalation of air, medicated by vapors from volatile oils and other suitable substances.

This invention also provides an excellent 35 means for maintaining the proper humidity in the air, or for supplying perfumes to the air in theatres, stores and homes.

A further object of the invention is to provide a vaporizing device which is easy 40 to assemble, cheap to manufacture, easy to fill, clean and repair.

A further object of the invention is to provide a vaporizing pan adapted to be mounted upon any standard size incandescent bulb and to form a reflector therefor. 45 A further object is to provide a vaporizing device adapted to be mounted upon a standard size incandescent lamp bulb regardless of the angle at which the bulb is mounted, 50 and adapted to be suspended on the bulb so that the contents will not spill.

A further object is to provide a one-piece 55 vaporizing pan which is made in one piece and requires no screws or other attaching devices. A further object is to provide a vaporizing device which is efficient in opera-

tion, cheap to manufacture, and easy to fill, clean and attach. Other objects will be apparent from the following description and accompanying drawings.

The following description and accompanying drawings set forth in detail certain means embodying the invention, the disclosed means, however, constituting but one of the various mechanical forms in which the principle of the invention may be employed.

Referring to the accompanying drawings forming a part of this specification, Fig. 1 is a side elevation of the air purifying device mounted upon a lamp bulb, various positions of the lamp bulb being shown in dotted lines and a portion of the pan being broken away and shown in section; Fig. 2 is a perspective view of the device; and Fig. 3 is a side elevation showing the vaporizing pan mounted upon an upwardly projecting bulb such as the bulb of a pedestal lamp, the bulb being shown in dotted lines at an angle with respect to the vertical.

Referring to the accompanying drawings, the air purifier consists of a vaporizing pan formed in one piece from sheet metal to provide an annular trough 10 to receive the fluid to be vaporized. The pan is provided 85 with an outer cylindrical wall 11, a flat bottom 12, and an inner annular wall 13, the upper portion 14 of which projects above the upper edge of the outer wall 11, and is curved inwardly converging to a central 90 circular top opening 15.

The opening 15 is of a diameter less than the maximum diameter of a standard incandescent lamp bulb, but of greater diameter than the neck of the bulb, so that 95 the neck of the bulb may be inserted through the opening 15 from the bottom and screwed into its socket. The vaporizing device can thus be suspended from a lamp, as shown in Fig. 1 of the drawing, the upper edge of 100 the inner wall of the pan engaging the bulb 16 between the neck portion thereof and the portion of maximum diameter. The inside of the inner wall 13 will be provided with a reflecting surface so that the device serves 105 as a reflector for the lamp as well as a vaporizer. Since the opening 15 is of considerably greater diameter than the neck of the bulb to which it is attached, the bulb may be disposed at various angles with respect to the vertical, as shown in dotted lines 110 at 16° in Fig. 1.

The vaporizing device may be set upon an upwardly projecting lamp bulb 16', as shown in Fig. 3, and in dotted lines in Fig. 1, and the upwardly projecting lamp bulb 5 may be disposed at various angles to the vertical, as shown in dotted lines in Fig. 3.

The trough 10 of the pan may contain a suitable liquid or solution for supplying the desired ingredients to the atmosphere of the 10 room in which the device is used. If it is desired to supply humidity to the air, water will be placed in the trough 10. For disinfection, suitable fluid insecticides or germicides may be employed. For medicinal 15 treatments, suitable medicinal substances such as balsams, tinctures, volatile oils, etc., may be employed. For air purifying purposes, suitable deodorants and disinfectants suitable for inhalation may be employed.

20 An annular removable filler 17 of absorbent material may be placed within the trough 10 which is adapted to be saturated with the liquid which is to be vaporized. This filler is preferably of heat retaining material 25 and a non-organic substance which will not be chemically acted upon by liquids which are to be vaporized. Asbestos has been found to serve very well for this purpose. This absorbent holder for the liquid serves to retain 30 heat and causes the same to be more evenly distributed facilitating the vaporization and preventing overheating of the liquid adjacent the heated wall of the pan. Substances such as some of the volatile oils 35 which are injuriously affected by light or excess heat are protected against deterioration. Additionally the absorbent prevents spilling of liquid should the pan be accidentally tipped. In case the pan when used 40 becomes tilted so that its bottom is somewhat inclined to the horizontal the liquid will still be held by capillary attraction uniformly distributed throughout the filler.

Having described my invention, I claim:

45 1. A vaporizing pan comprising an annu-

lar trough having an outer substantially circular wall and an inner wall concentric with the outer wall, said inner wall being rounded inwardly toward the top thereof to provide at the opening an edge portion engageable 50 with an incandescent lamp bulb whereby the pan may be supported at different angles with respect to the axis of a bulb.

2. A vaporizing pan comprising an annular trough having an outer substantially circular wall and an inner wall concentric with the outer wall, the major portion of the inner wall being of a diameter materially greater than the enlarged portion of an electric light bulb and tapering inwardly adjacent its upper edge to an opening of less diameter than at the bottom whereby the upper edge portion of said wall forms a supporting seat engageable with a rounded portion of a lamp bulb to support the pan 65 therefrom at various angles with respect to the axis of the bulb.

3. A vaporizing pan comprising an annular trough having an outer substantially circular wall and an inner wall concentric with the outer wall, said inner wall being rounded inwardly toward the top thereof to form a seat for engagement with an incandescent lamp bulb, the inner wall being adapted to be supported out from the bulb and the inner surface of said inner wall having a reflecting surface.

4. A vaporizing pan having a layer of absorbent material on the bottom thereof.

5. A vaporizing pan having a porous layer 80 of asbestos on the bottom thereof.

6. A vaporizing pan comprising an annular trough having the inner wall thereof formed to rest upon an incandescent lamp bulb and a removable filler of absorbent material in the trough.

In testimony whereof, I hereunto affix my signature.

FRANK C. DORMENT.
